METAL POURING MECHANISM

Frank D. Mascaro, Ben Avon, Pa., assignor to
American Steel Foundries, Chicago, Ill., a corporation of New Jersey

Application August 23, 1947, Serial No. 770,272

2 Claims. (Cl. 22—82)

1

This invention relates to a tilting mechanism for a foundry pot or ladle and more particularly to a latch mechanism or safety device for the tilting mechanism to prevent accidental tilting of the pot.

One object of the invention is to provide a positive locking, manually releasable latch mechanism for maintaining the pot in upright position to prevent the pot from accidentally tilting on the trunnions from which it is suspended and thus spilling molten metal when it is being transported from place to place in the foundry.

Another object of the invention is to devise a latch mechanism which is easy to operate, is of simple construction, and is capable of withstanding severe use in service.

These and other objects of the invention will be apparent from the specification and the drawings, wherein:

Figure 1 is a side elevation of one form of my invention with the keeper and hand guard being shown in vertical section;

Figure 2 is a view taken from the right of the structure shown in Figure 1;

Figures 3 to 5 illustrate my novel keeper, Figure 3 being a top plan view thereof, Figure 4 being a side elevation thereof taken from the bottom as shown in Figure 3, and Figure 5 is an end view thereof taken from the right as shown in Figure 3; and

Figures 6 and 7 illustrate another form of my invention, Figure 6 being a top plan view thereof, and Figure 7 being a side elevation thereof.

Describing the invention in detail and referring first to the modification shown in Figures 1 to 5, the pot or ladle 2 is provided with horizontally extending trunnions 4 and 6 upon which the pot may be suspended from hangers 10 and 12 forming part of a bail, the lower or hook ends 14 and 16 of the hangers being hooked under the trunnions 4 and 6, respectively, and the upper ends of the hangers being connected in any convenient manner as by nuts 18, 18 to a cross piece 20 designed for connection to an overhead means (not shown) for conveying the pot.

The pot, after having received a charge of molten metal, is poured or teemed by hand into the molds by rotating the pot on the trunnions by means of a lever or tilting handle, generally designated 22, said handle being in the form of an L-shaped bar comprising a vertical extension or upstanding arm 24 spaced from the pot and a horizontal extension or arm 26 (Figure 1) extending parallel to the axis of the trunnion 4.

and having a down-turned portion 28 at its inner end adapted to fit into a socket 30 in said trunnion 4 for thus removably keying the handle to the pot, it being understood that movement of the handle will effect corresponding movement of the pot.

A sheet metal shield or hand guard, generally indicated at 32, is provided at the upper end of the arm 24. The guard is, in general, semi-cylindrical in form and comprises top and bottom webs 34 and 36 connected at vertically spaced points as at 38 and 40, respectively, to the arm 24 of the tilting handle in any convenient manner as by welding. A semicylindrical web 42 extends between the top and bottom webs and is connected at its upper and lower edges as by welding at 44 and 46 to the edges of the top and bottom webs remote from the arm 24. The web 42 with said top and bottom webs defines a pocket 48 large enough to conveniently admit an operator's hand, the guard serving to protect the operator's hand from the heat radiated by the molten metal in the pot.

A V-shaped elbow lever or latching member 50 is disposed in the pocket 48, said lever being pivoted at its elbow on a pin or bolt 52 extending through said lever 50 and through a pair of lugs 54, 54 fixed to the arm 24 at a point intermediate the points of connection 38 and 40 between the arm and the top and bottom webs of the guard.

The lever 50 comprises a diagonally upwardly extending leg 56 (Figure 1) and a horizontally extending leg 58, the leg 58 merging at one end into the lower end of said leg 56 and at its other end extending through an opening 60 in the web 42 of the guard. It will be noted that the leg 56 serves as a handle for operating the latching member, and the leg 58 serves as a latching bolt as hereinafter described.

A stop lug 62 (Figure 1) is formed on the lever 50 on the outer side of the elbow formed by the juncture between the legs 56 and 58 thereof, said lug 62 being adapted for abutment as at 64 against the arm 24 to limit counterclockwise rotation (Figure 1) of the lever 50 for a purpose hereinafter described.

A keeper or socket member, generally designated 66 and illustrated in detail in Figures 3 and 5, is sleeved over the hanger 10 of the bail and may be fixed thereto as by welding. The keeper comprises a cylindrical portion 68 with an opening 70 accommodating sleeving of the keeper onto the hanger 10. A pair of spaced vertical webs 72 and 74 extend from one side

of said cylindrical portion, said vertical webs merging at their upper ends into a horizontal web 76 extending therebetween, said horizontal web 76 merging at its inner end into the cylindrical portion 68 and being downwardly offset as at 78 at its outer end and with said side webs defining a socket 80 adapted to receive the adjacent end of the leg 58 of the latch member 50 when the pot is in an upright position. The web 72 is formed with an upwardly extending lug 82 at one side of the socket 80, said lug 82 serving as a stop, it being adapted to abut against the adjacent end of the leg 58 when said leg 58 is in raised position to prevent backward tilting of the pot. At the opposite side of the socket 80 the web 74 is formed with a laterally extending downwardly sloping web 84 which, as herein-after noted, is adapted to guide the leg 58 into the pocket 80 when the pot is being returned from a tilted position to its upright position. A pair of vertical depending webs 88 and 90 are formed at opposite sides of the web 84, said webs 88 and 90 merging at one end into the web 74 and at the other end merging into a vertical depending web 92 extending therebetween and integrally formed with the leading edge of the web 84. The web 90 is continued on the forward edges of the webs 76 and 72 and is cored away at the socket 80.

In operation, to tilt the pot from its upright position after it has been charged with molten metal, the operator inserts his hand into the guard pocket 48, simultaneously grasping the arm 24 of the tilting handle and the handle portion or leg 56 of the lever 50 and, by squeezing his hand, rotates the lever 50 in a clockwise direction (Figure 1), causing the lever to assume the position shown in phantom lines in Figure 1, thus lifting the leg 58 or bolt portion of the lever out of the socket 80. The tilting handle may then be rotated in a clockwise direction (Figure 2), counterclockwise rotation or rearward tilting of the pot and handle being prevented by the stop lug 82. The operator, after having tilted the pot as described, may release his hold on the latch member. After completing each pouring operation the operator may rotate the pot to an upright position. As the pot and tilting handle are being rotated to the upright position, the latch member, if in the released position as shown in phantom lines in Figure 1, is caused to rotate in a counterclockwise direction by gravity, the leg 58 of the latch member being provided with a lug 86 to increase its weight and cause such movement. The latch member is limited in this rotation by the stop lug 62 which, after the latch member assumes a certain predetermined position, abuts against the arm 24 of the tilting handle. As the rotation of the pot to its upright position continues, the leg 58 of the latch member engages the sloping web 84 of the keeper and rides thereon, thus being guided into the socket 80, the leg 58, after reaching the socket, dropping thereinto of its own weight.

If the operator should accidentally release his hold on the tilting handle when the pot is in tilted or pouring position, the pot and handle will be caused to rotate to an upright position inasmuch as the trunnions 4 and 6 are above the center of gravity of the pot and it will be observed that as the pot swings to such upright position, the latching member will act in the same manner as when the pot is intentionally rotated from the tilted to the upright position.

As an alternative, the operator may hold the

latch member and tilting handle in all positions of the pot and may, upon completion of the pouring operation, bring the tilting handle to an upright position and simultaneously release the latching member and tilting handle, whereupon the leg 58 of the latching member will drop into the pocket 80 of its own accord.

Referring now to Figures 6 and 7 illustrating another modification of the invention, the ladle 10 or pot carrier 100 is substantially square in top plan view and is adapted to receive a pot 102 of complementary form therein in the usual manner to afford support therefor, the pot being shown in Figure 7 in phantom lines.

The carrier is provided with shields 106, 108 and trunnions 108 and 110 at diagonally opposite corners thereof. The trunnions 108 and 110 are rotatably mounted on the lower ends of a pair of hook bolts or hangers 112 and 114 forming part 15 of a bail which is designed for connection to overhead means (not shown) for conveying the pot in a manner as will be readily understood by those skilled in the art. The trunnion 108 is formed with an L-shaped tilting handle or lever 116, the handle being adapted to be grasped by an operator and rotated to tilt the pot. The vertical leg of the handle 116 mounts at its upper end and L-shaped guard 118 comprising a horizontal web 120 and a vertical web 124, said horizontal web being connected as at 122 (Figure 7) to said vertical leg of the handle intermediate the top and bottom thereof, and said vertical web 124 being disposed intermediate the vertical leg of the handle and the pot. A V-shaped bell 20 crank lever 126 is pivoted at its elbow as at 128 to a pair of lugs 130, 130 on the vertical leg of the tilting handle, the lugs being disposed below the horizontal web of the guard. The lever 126 comprises a diagonally upwardly extending leg 132 projecting through a slot 134 (Figure 6) in the horizontal web of the guard and a leg 136 angularly related to the leg 132, the leg 136 normally underlying the horizontal web of the guard. The free end of the horizontal leg 136 is pivoted as at 138 to one end of a downwardly extending rod 140, the opposite end of which is pivoted as at 142 to a link or latching bolt 144 intermediate the ends thereof. The link 144 is pivoted at one end as at 146 to a pair of lugs 148 on the horizontal leg 150 of the tilting handle. The free end of the link 144 extends towards the adjacent hanger 112 and in the locked position of the pot is disposed at one side of a keeper or catch 152 which is in the form of a plate fixed to one of the legs of the hanger 112. At the opposite side of the plate 152 is disposed a vertically extending lug 154 formed integrally on the horizontal leg of the tilting handle adjacent the trunnion 108, the lug 154 being adapted to abut against the adjacent side of the keeper 152 to prevent backward tilting of the pot, and the link 144 being adapted to abut against the opposite side of the keeper when the pot is in a locked upright position to prevent forward tilting of the pot.

In operation, to tilt the pot from its upright locked position, the operator inserts his hand into the guard, simultaneously grasping the vertical leg of the tilting handle and the diagonally extending leg of the bell crank lever and, by squeezing his hand, rotates the lever in a counterclockwise direction (Figure 7), thus raising the leg 136 thereof and causing the lever to assume the position shown in phantom lines in Figure 7, the web 124 of the guard being slotted as at 156 (Figure 7) to accommodate such movement. The

lever raises the rod 140, which in turn raises the free end of the link 144 above the keeper 152 whereupon the pot is permitted to be rotated forwardly for pouring. Upon the completion of each pouring operation, the operator again raises the link 144 by actuating the bell crank lever and, upon returning the pot to its upright position, releases the bell crank lever whereupon, due to gravity, the bell crank lever is caused to rotate in a clockwise direction (Figure 7), the rod connected thereto moving downwardly and the link 144 dropping behind the keeper 154.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. The combination of a pot having trunnions, a bail rotatably suspending said pot from said trunnions, one of said trunnions having a transverse opening therethrough, means for rotating the pot for teeming the same, said means comprising a handle member having an end portion extending through said opening for removably interlocking said member with the pot, said member having an intermediate portion extending from said end portion away from the pot and seated on top of said one trunnion, a handhold portion integral with said intermediate portion and extending angularly thereto, said handhold portion in the upright position of the pot being located in the vertical plane of said bail, and means for releasably locking the pot in upright position comprising a latch element disposed between said handhold portion and said bail and comprising a pair of angularly related interconnected legs, means pivotally connecting said element at the juncture of said legs with said handhold portion on an axis disposed between said handhold portion and bail and angularly related to said plane, one of said legs sloping upwardly from said axis away from said handhold portion toward the bail, the other of said legs extending generally perpendicular to said handhold portion toward said bail, a keeper on said bail disposed below said other leg and having an upwardly open socket receiving an end of said other leg therein, an abutment lug on said keeper extending upwardly at one side of said socket, a downwardly sloping web at the opposite side of the socket, said legs being rotatable toward and away from said bail and, when rotated away from said bail, raising said other leg out of said socket whereupon said member may be rotated to teem said pot, a lug at the juncture of said legs extending downwardly from said axis toward said handhold portion, said lug being adapted to abut against said portion to limit rotation of said element toward said bail to prevent said other leg from moving to a position below said keeper when said handle member is rotated from upright position whereby when said handle member is ro-

tated from an inclined to an upright position said other leg is caused to engage said sloping web and to slide thereon into said socket, said handle member being disconnectable from said keeper in the upright position of said handle member by lifting said handle member upwardly to withdraw said end portion of said handle member from said opening in the trunnion and lift said other leg of said latch member out of said keeper socket.

2. The combination of a pot, a bail rotatably suspending the pot, a handle connected to the pot for rotating and teeming the same, said handle having a handhold portion extending upwardly in the upright position of the pot, and means for releasably locking the pot in upright position comprising a latch disposed between the handhold portion and the bail and comprising a pair of angularly related legs, means pivotally connecting said latch at the juncture of said legs with the handhold portion on an axis extending angularly to the plane of the bail, one of the legs sloping upwardly from the axis toward the bail and the other leg extending generally perpendicular from said handhold portion toward the bail, a keeper on the bail below said other leg and having a socket receiving said other leg therein, an inclined surface on the keeper sloping downwardly at one side of said plane and extending to said socket, said latch being manually rotatable away from the bail by grasping said one leg and portion together to raise said other leg out of the socket whereupon said handle may be rotated from an upright to an inclined position for teeming the pot, and a lug at the juncture of said legs extending downwardly from said axis toward the handhold portion for abutment therewith to limit rotation of the latch toward the bail to prevent said other leg from moving to a position in a path below the keeper when the handle is inclined and the latch is released whereupon, when said handle is rotated to upright position, said other leg is positioned in a path intersecting said sloping surface whereby said other leg is caused to slide on said surface into the socket.
